CARL PONTOPPIDAN, OF COPENHAGEN, DENMARK, ASSIGNOR TO F. L. SMIDTH & CO.,
OF NEW YORK, N. Y., A CORPORATION OF NEW JERSEY

GRINDING CEMENT MATERIALS, ETC.

Application filed December 30, 1927, Serial No. 243,530, and in Great Britain October 8, 1927.

Experience has shown that in the grinding of cement and kindred materials, the temperature at which the grinding process is effected has a considerable influence on the fineness to which the cement or the like can be ground and on the properties thereof, and that this influence is particularly pronounced in cases in which it is required to grind the material very fine.

10 If the temperature, in the portion of the grinding mill in which the grinding of cement material, for instance, is effected, exceeds about 100° C. the ground material has a tendency to clog or adhere to the surfaces 15 of the mill and of the grinding bodies, etc. with which the material comes in contact during the grinding and, consequently, the effectiveness of the grinding bodies is reduced during their operation upon the material to be ground, to such an extent that 20 at this higher temperature they are unable to grind the same quantity of material to the same degree of fineness as at lower temperatures, at which the material does not 25 adhere to the grinding bodies.

Since the power required for driving the grinding mill remains substantially the same whether the grinding is performed more or less efficiently, the clogging of the 30 material to be ground on the grinding bodies and grinding surfaces actually reduces the efficiency of the mill to a considerable extent.

A series of practical experiments with 35 various kinds of grinding mills has shown that the efficiency of the mills may be as much as 33% lower at the higher temperatures at which clogging occurs than in cases of lower temperatures at which no clogging occurs.

40 In addition to the clogging of grinding bodies and grinding surfaces by the material being ground, the rise of temperature in the mill during the grinding process may also cause other serious troubles. For example, 45 cement which has been exposed during grinding to a rise of temperature as indicated above has a time of setting which is considerably shorter than is admissible for 50 standard sound cement, so that the rise of

temperature has a directly injurious effect on the quality of the cement.

In order to eliminate the troubles due to a high rise of temperature it has been proposed heretofore to sprinkle the grinding mill externally with water during the grinding process. This procedure, however, requires very considerable quantities of cooling water, and in many cases the grinding mill, such as a tube-mill, must be surrounded for this purpose by a cooling-jacket, which causes considerable inconvenience as regards accessibility of the grinding mill for inspection and the like.

It has also been proposed, instead of 65 sprinkling the grinding machine with water, to add water, prior to the grinding, that is, before the material enters the mill, to the material to be ground. Such addition of water, however, has to be made very cautiously when grinding cement, for instance, and only to a very limited extent as, owing to the temperature being considerably below 100° C., there is danger of a chemical action taking place between the added water 70 and the material to be ground, so that the water may combine with the cement dust during the first stage of the grinding process and clog the passages, etc. of the grinding mill.

80 Although the limited quantity of water which may be added to a material before grinding may assist in reducing the temperature during the first stage of the grinding process, it will not prevent the temperature of the material to be ground from increasing to such an extent, during the last stage of the grinding in which a reduction of the rise of temperature is of greatest importance, as to prevent the above mentioned 85 difficulties from being created. The quantity of water added before grinding will in fact partly evaporate and partly combine with the dust formed by the material to be ground, so that no water will be left to bind, that is, to absorb, by its evaporation, a sufficient portion of the heat developed during the subsequent and final part of the grinding process to reduce the temperature. This 90 is particularly true when the material is to 95 100

be ground to a very high degree of fineness as the amount of heat produced during the last stage of such grinding is very large, and the material to be ground is more inclined to adhere to the grinding surface the higher its degree of fineness.

The present invention has for its object to overcome the difficulties referred to and it accomplishes this purpose by the addition 10 to the material to be ground, of an evaporable substance such as liquid in such manner that when it is exposed to the action of the heat produced by the grinding operation it will, by its evaporation, bind or absorb 15 so much heat that the material will be cooled to a temperature below the critical temperature of the particular grinding process, that is, the temperature at which the material shows an appreciable tendency to adhere to 20 the surfaces of the mill and of the grinding bodies with which it comes into contact.

By reason of the large quantity of heat required to evaporate the added substance, such as water, the quantity of the added substance required will be relatively small,— 25 as a rule only about one to three per cent of the weight of the material ground. For this reason the present process becomes very much simpler and more convenient to carry 30 out than the processes known hitherto. The quantity of evaporable substance is measured previously to being added or while being added, and is conveyed to the grinding mill in any suitable manner as through a suitable 35 pipe line which, in case of tube-mills for example, may be introduced through one of the end trunnions of the mill, preferably through the trunnion provided at the discharge end of the mill. If the supply pipe 40 is inserted through an end trunnion, it will not be necessary to connect it rigidly to the mill, but it may be fitted freely through the trunnion and a hole in the end screen of the mill. In tube-mills the supply pipe may 45 be passed axially into the mill through the inlet end of the latter or, more suitably, through the outlet end, and may then pass either axially through the mill or along the inner or outer wall of the same to the point 50 where it is desired to supply the liquid. At this point the supply pipe may terminate, if desired, in a spreader or atomizing device whereby the liquid is atomized or spread into the mill and, consequently, may be distributed quickly over the interior of the desired part of the mill.

The accompanying drawing shows diagrammatically two different embodiments of 60 the invention.

Figure 1 is an outline view in longitudinal section of a tube-mill in which the supply of liquid is effected through the discharge end of the mill, and

65 Figure 2 is a similar view of a tube-mill

in which the supply is effected through the inlet end.

The tube-mill is shown as having three chambers I, II, III, and as having associated with it a storage bin *a* from which cement clinker for example is fed to the mill by means of a feeder table *b* and a supply funnel *c*. The finished ground cement passes out of the mill *r* through one of the end trunnions *d* and a controlling screen *e*, 70 and then falls through a pipe *f* on to a conveyor, not shown. At *g* is indicated an exhaust flue for the vapor generated in the mill in consequence of the addition of water to the same, as hereinafter described.

In the construction shown in Figure 1 water is introduced into the last grinding chamber III of the mill by means of a tube *l* inserted through the end trunnion *d* into the grinding chamber III and connected, at its outer end, to a pump *j* which is supplied with water through a pipe *i* from a pipe *h*, fitted with regulating valve *v*. The pipe *l* is provided with a packed joint *k*, and at the end of the pipe *l*, inside of the mill, is a spreader *m* or the like. The pipe *l* may be supported in the mill, with which it rotates, by means of rods *n*. By means of the spreader *m* water in a finely divided or preferably atomized state is supplied constantly and in small quantity to the grinding bodies in the grinding chamber III, and by the absorption of heat in its evaporation the temperature in the said chamber is maintained within suitable limits.

The temperature of the material leaving the mill may be observed by means of a contact thermometer *p* inserted in the pipe *f*. The material directed from the bin *a* into the mill may also pass a contact thermometer *o* in the discharge spout of the bin to indicate the temperature of the material supplied to the mill.

Through the proper functioning of the contact thermometers *o* and *p* it can be determined when the permissible temperature limits have been reached, and therefore when an increase or reduction in the addition of liquid is required in order to maintain the temperature of the material within definite limits.

The general arrangement of the construction shown in Figure 2 differs from that shown in Figure 1 merely in that the supply of liquid is effected through the inlet end of the mill. After having passed the pump *j* and the packed joint *k* the liquid-supply pipe *l* passes through the end trunnion *t* at the inlet end of the mill, and is then extended radially out through the latter and then parallel to the axis of the mill along the outside of the mill to the point, in the present case the central chamber II, where it is desired to supply the liquid. In this case also the supply pipe terminates in

a spreader or atomizer *m* attached, centrally of the mill, to the last portion *s* of the liquid-supply pipe which is extended diametrically across the mill.

5 In cement grinding it is desirable to supply the liquid or other evaporable substance at a point in the mill where the temperature differs only slightly from the temperature, as a rule 100° C., at which the substance evaporates. However, since the substance, particularly a liquid, will generally be distributed over a large area within the grinding machine when it is supplied thereto, it would be only approximately correct to refer to a definite temperature of the material or to a definite point of the mill at which the supply of liquid is to be effected. It would be more correct to refer to a zone of supply. In tube-mills for grinding cement 10 the location of this zone depends upon many different factors, such as the temperature of the clinker supplied to the mill, the quantity of heat conveyed to the surroundings by the surface of the mill, the shape and nature of 15 the grinding bodies, the power consumption and the output of the mill, the hardness of the material treated etc. All these factors determine in fact the production of heat during the grinding and, consequently, the temperature to which the material is heated. For these reasons the zone to which the liquid is supplied may be located, according to circumstances, at widely varying points of the grinding machine. In multi-chamber 20 mills constructed according to the tube-mill principle it may even be desirable to supply the liquid in several different zones. For instance, if the mill has three chambers, then the liquid may be supplied to the second and 25 third chambers, while under other circumstances it may be advantageous to supply the liquid to two different zones of one and the same chamber, such as the third chamber.

Substances which for some reason or other 30 are desired to be mixed with the ground material may be added to the same together with the substance used for cooling the material. Such other substances, in the case of cement grinding, such as chloride of lime, 35 sulphate of lime, tannin and other known admixtures, may suitably be suspended or dissolved in the evaporable liquid before the latter is introduced into the mill.

40 I claim as my invention:

45 1. The improvement in the grinding of cement material, which consists in adding to the material while it is being ground a substance evaporable by the heat developed in 50 grinding whereby, through the absorption of heat in the evaporation of such substance, the temperature of the material being ground is reduced, the substance being added in such quantities and when the temperature 55 of the material is such that the substance is

evaporated without absorption by the material.

2. The improvement in the grinding of cement material, which consists in adding to the material while it is being ground a liquid evaporable by the heat developed in grinding, whereby, through the absorption of heat in the evaporation of the liquid the temperature of the material being ground is reduced, the liquid being added in such 70 quantities and when the temperature of the material is such that the liquid is evaporated without absorption by the material.

This specification signed this 10th day of December, A. D. 1927.
